UNITED STATES PATENT OFFICE.

LYMAN D. HALL, OF NEW YORK, N. Y.

VANITY HAND BAG.

Application filed February 10, 1927. Serial No. 167,185.

This invention relates to an article intended for personal use, in the form of manikin or figure, which is so constructed and arranged as to constitute a purse or hand-bag 5 of convenient form, which utilitarian feature does not, however, materially detract from the ornamental appearance of the figure or manikin. Preferably, according to this invention, the figure is in the form of an 10 animal, a dog for instance.

Further, according to this invention, the figure may be made of cloth, fur, or imitation fur, and is in part stuffed or filled with some soft material, the body or main portion, how- 15 ever, being made hollow to provide a pocket which, being suitably lined, may be used for the reception of such articles as are usually carried in a hand-bag, purse, or vanity case. Access is had to this pocket through a slit 20 preferably running longitudinally of the body, and this slit is preferably closed by a self-locking fastening device, which is commercially known as "lock-tight".

According to the present invention, the 25 manually operable part of the self-locking device may constitute an essential part of the figure as, for instance, the tail, and further this manually operated part may comprise a sound-producing element adapted to make 30 a noise in imitation of the animal which may be used for amusement purposes and also to indicate when the self-locking device is being opened by an unauthorized person, for in such case the unauthorized person would 35 grasp the manually operable part and cause the sound-producing device to operate.

Other features and advantages will hereinafter appear.

In the accompanying drawings, which 40 show one form of the present invention, that at present preferred—

Figure 1 is a longitudinal view partly in section, showing the article and its construction, and particularly the pocket for recep- 45 tacles into which articles may be placed to be carried.

Fig. 2 is a top plan view of the article, showing the self-locking fastening device open to give access to the pocket.

Fig. 3 is a perspective view, showing how the article is carried.

The article of the present invention, as above indicated, is neither solely a purse or hand bag for utilitarian purposes, nor is it 55 solely a novelty or toy for ornamental pur-

poses. Yet, it has the attractiveness of a novelty or toy and the usefulness of a hand bag or purse. It will, however, for convenience, be called a bag hereinafter.

Heretofore, figure toys have been made, 60 and at times it has been the vogue for women and children to carry these toys, much as it is now the vogue for such persons to carry small dogs known as "toy dogs" because of their small size. Also, as is well known, it 65 is a practically universal custom for women to carry bags and purses, not only for the utilitarian purposes but also for their ornamental effects.

With this in mind, the article of the present invention was evolved, and this article, as above stated, serves both as a toy to be carried and as an attractive and novel hand-bag or purse. This is accomplished by constructing and arranging the figure toy so 70 that portions of it are made relatively stiff so that it may be conveniently handled and held on the arm of the user as a live dog would, and so that the main or body portion of the figure is hollow to form a pocket 75 for holding articles such as would be carried ordinarily in a hand-bag or purse.

In the accompanying drawings, the figure-toy is shown as a dog made of velvet or other fur-like cloth 8 sewed to provide a hollow 80 form 9. Of course, the article may be made in the form of other animals and of other materials, if desired.

The head 10 of the figure-toy may be made in any suitable way and may have a 90 stuffing 11 of cotton-batting or excelsior or other suitable material, and this stuffing 11 preferably extends into and through the neck 12 sufficiently to keep the head from dangling unnaturally when the article is being held on the arm of the user, as shown in Fig. 3. The fore legs 13 and hind legs 14 are filled with cotton wads 15, so as to 95 present a more or less natural appearance according to the amount of work and material which can be expended on the article, commensurate with its sale price. The shape of the legs 13 and 14, however, and the filling wads 15 should extend high enough and should be sufficiently substantial and 100 solid so that the article may be conveniently handled; conveniently held on the arm, as shown in Fig. 3, with the fore legs 13 above the arm and the hind legs 14 below the arm, the mid-section or body 16 being held 105

110

between the arm and the body of the user; and will not fall in a shapeless mass when laid down.

The mid-section 16, or body, is, according to this invention, left unfilled so as to provide a pocket 17 for the reception of such articles as are usually carried in a hand-bag or vanity case, such as handkerchiefs, a purse, compact, etc. The pocket 17 is preferably defined and beautified by a suitable lining 18, such as of silk. This lining 18 may be so made that the entire pocket 17 is used, or only so much thereof as desired.

At this point it should be noted that articles, such as a handkerchief carried in the pocket, tend to fill out the body of the figure and make it appear more natural. Yet, the pocket should preferably be of such size that in ordinary use the insertion of these articles does not distend the body parts 16 or even completely fill it out, for the article is more conveniently carried when the mid-section or body is pliant or yielding.

Access is had to the pocket 17 through a slit or opening 19, preferably extending longitudinally of the body 16, and this may be closed by a band or other conveniently closing means. Preferably, however, the sides of the slit 19 are connected to opposite sides of an interlocking fastening device 20 comprising interlocking catches 21 and a finger-piece 22 adapted, as usual, to cam the catches into and out of interlocking relation with each other when the finger-piece 22 is drawn along the catches in one direction or the other. When the slit 19 is closed by the operation of the finger-piece 22, the pocket is safely closed against the loss of even the smallest article which it would ordinarily contain.

Preferably, the slit 19 extends along the longitudinal center of the body 16 at what would be either the belly or back (as shown) of the figure. When this is done, it is advantageous to connect the tail 23 of the figure to the finger-piece 22 and have the interlocking catches 21 so arranged that they are interlocked by movement of the finger-piece from the fore-quarter to the hind-quarter of the figure, and then terminate in such position that the tail 23, connected to the finger-piece 22, will be located in its natural place when the slit 19 is closed.

It should be understood that the present invention is not limited in its more specific aspects to the precise location of the slit 19, to the means of closing it, or the use of the tail 23 as the manually operated part. For, while the arrangements described are extremely advantageous, the slit 19 may be otherwise arranged, and any other extremity or appendage of the figure or another extra part may be used to operate the interlocking catches with good results.

65 This invention also embraces, along with

the other features referred to and in combination therewith, a device for making a noise in imitation of the barking of a dog, or a sound made by an animal represented by the figure.

This means preferably is located in some appendage as, for instance, the tail 23, and may comprise a rubber bulb 24 connected to a pipe 25 containing a reed 26 or other vibrating body. When the bulb 24 is 75 squeezed, air is forced through the pipe to cause vibration of the reed 26 with the result that a sound is produced.

The sound-producing or barking device may be used for amusement purposes. It is 80 particularly advantageous in its arrangement with the other parts of the article, for, when located in the tail 23 and when the tail is the part grasped by hand when opening the pocket, a person tampering with the 85 article may be easily detected, because when the tail 23 is grasped to open the slit 19 the sound-producing device operates to give an alarm.

Variations and modifications may be made 90 in accordance with this invention, and portions of the improvements may be made without others.

Having thus described the invention, what is claimed as new and for which it is desired to obtain Letters-Patent, is:—

1. A hand-bag comprising an animal-shape in the form of a quadruped made of fur or fur-like material in hollow form and having fore legs and hind legs and head 100 stuffed so as to be semi-solid and its mid-section or body portion unstuffed and pliant, the mid-section being provided with an article receiving pocket adapted to be partially filled with articles placed therein to 105 give the mid-section a natural appearance, the animal-shape being formed with fore legs and hind legs extended from the body and sufficiently spaced apart to embrace the arm of the user and thus prevent accidental 110 displacement when the article is confined at its mid-section between the arm and the body of the user.

2. A hand-bag comprising an animal-shape in the form of a quadruped made of fur or fur-like material in hollow form and having fore legs and hind legs and head 115 stuffed so as to be semi-solid and its mid-section or body portion unstuffed and pliant, the mid-section being provided with an 120 article receiving pocket adapted to be partially filled with articles placed therein to give the mid-section a natural appearance, the animal-shape being formed with fore legs extending from the body so as to overlie the arm of the user and thus prevent 125 accidental displacement when the article is confined at its mid-section between the arm and the body of the user.

3. A hand-bag comprising an animal- 130

shape in the form of a quadruped made of fur or fur-like material in hollow form and having fore legs and hind legs and head stuffed so as to be semi-solid and its mid-
5 section or body portion unstuffed and pli-
ant, the mid-section being provided with a slit extending longitudinally thereof, the
fore legs extending from the body so as to
overlie the arm of the user and thus pre-
10 vent accidental displacement when the arti-
cle is confined at its mid-section between the
arm and the body of the user, a lining in
said body constituting a pocket, the mouth
of which is in said slit, said pocket being
adapted to carry miscellaneous articles such 15
as are usually carried in a purse or hand-
bag, and means for closing said slit and
hence said pocket to retain said articles
therein.

Signed at New York, in the county of 20
New York, and State of New York, this
8th day of February, 1927.

LYMAN D. HALL.
